UNITED STATES PATENT OFFICE.

FREDERICK E. V. BEANES, OF HACKNEY WICK, LONDON, ENGLAND.

TOBACCO PIPE.

Application filed February 6, 1922. Serial No. 534,603.

To all whom it may concern:

Be it known that I, FREDERICK EDWARD VESSEY BEANES, a subject of the King of Great Britain, and resident of Falcon 5 Works, Wallis Road, Hackney Wick, London, E. 9, England, have invented certain new and useful Improvements in Tobacco Pipes, for which I have filed an application in England, dated December 22nd, 10 1921, of which the following is a specification.

This invention relates to tobacco pipes, and it has for its object to provide a pipe with an improved bore of bowl and stem, 15 enabling the smoke from the tobacco to be drawn through the pipe with less source of obstruction at the orifice from the bowl into the stem, thus giving a free draught at all times, more complete combustion of 20 the tobacco and dispersal of condensed moisture.

The invention will be described with reference to the accompanying drawing wherein:

25 Figure 1 shows a pipe in longitudinal vertical section.

Figure 2 shows the same in plan view.

Figure 3 shows the bowl of the pipe in 30 transverse vertical section on the line 3—3 of Figure 1.

Figure 4 is a sectional view corresponding to Figure 1, showing a form of pipe as used to a large extent hitherto.

Figure 5 is a similar sectional view to 35 Figure 1 showing the invention as applied to a pipe of another shape.

Referring first to Figures 1 to 3, it will be seen that the bowl *a* of the pipe is first bored out to form a rounded conical or 40 paraboloid bore *l* as is usual, and then a recess is formed at the lower end of the bore *a* as at *b* by the use of a milling cutter for example, this recess forming an extension of the bore *l* adjacent the place where 45 bore *m* of the stem *c* of the pipe communicates with the bore *l*. The side face of this recess *b* is approximately parallel with the axis of the pipe bowl *a*, i. e. approximately at right angles to the axis of the stem *c* 50 of the pipe in the case of a straight pipe as in Figures 1 to 3. The stem *c* of the pipe is bored out so as to provide a comparatively wide bore *m* extending nearly to the bore *l*, but terminating in a conical or tapering portion *d* so as to provide an aperture 55 or draught hole at *e* where the bore *m* opens

into the recess *b*. This draught hole *e* is small enough to retain the tobacco in position in the bowl while permitting the smoke to be drawn freely through it into 60 the bore of the stem *c*; and the rapidly enlarging bore at *d* back of the hole *e* insures that no particles which may pass into the hole *e* will remain therein and cause an obstruction, because any particle small 65 enough to pass through hole *e* can be drawn through it at once into the wider bore *m* in the stem, and can remain there without obstructing the draught passage through *e*. The stem has a mouthpiece fitted to the 70 same in any usual or convenient manner, a mouthpiece being indicated in dotted lines at *f* in Figures 1 and 2.

When the tobacco is pressed down in the bowl of the pipe, the pressure at the side 75 near the orifice *e* is relieved by the recess *b*, which does not become choked with tightly packed tobacco, because the tapering bore *l* of the bowl takes the pressure, and the recess at *b* is not large enough in relation to 80 the bore of the bowl to permit the tobacco to be pressed into it to any considerable extent. This insures a free draught at the hole *e*, resulting in better combustion of the 85 tobacco and dispersal of moisture which would otherwise tend to condense at the bottom of the bowl.

As the recess *b* is provided with a vertical side face *n*, the draught hole *e* will be out of the range of a pipe scraper or a knife 90 used for clearing out the bore *l*, so that there is no substantial risk of the hole *e* being enlarged by this operation. The hole *e* is further protected by the fact that it opens into the recess *b*, while a scraping 95 tool fitting into the normal bore of the bowl will be prevented by the general shape of the bowl cavity from engaging with the side face *n* of the recess adjacent the hole *e*.

It will be obvious that the tapering of the 100 bore *m* as at *d* will facilitate the cleaning out of the said bore, in that there is no sharp corner or shoulder *k* (see Fig. 4) in the bore *m* against which a cleaning member or wire can catch.

I have found in practice that pipes made in the manner described and illustrated in Figures 1 to 3 are in fact much more satisfactory in use than pipes made in the manner hitherto usual, as indicated for example 110 in Figure 4, which shows a pipe having a relatively long and small bore *g* opening at

h into the bottom of a bowl, which latter is bored out to a paraboloid curvature. The tobacco tends to be packed tightly at the opening *h* of the draught hole, and condensed moisture tends to pass directly into the draught hole. The shoulder at *h* also tends to obstruct the easy cleaning out of the bore hole in this case. On the other hand, in the pipe shown in Figures 1 to 3, I find that the tobacco burns cleanly and freely down to the bottom of the bore *l*, while the tendency to obstruction of the draught hole or to the drawing in of moisture through it is greatly reduced, and the satisfaction obtained from the smoking of such a pipe is therefore greatly increased.

The invention can be applied as indicated in Figure 5, to a pipe in which the stem *c* is at an acute angle to the axis of the bowl *a*, and from what has been stated above, this figure in which each part is lettered to correspond with corresponding parts in Figures 1 to 3, will require no further explanation.

It will be apparent that pipes according to this invention may be made of any suitable materials, and although the invention has been described as applied to pipes having the bowl and stem of wood or other natural material, the pipe may be moulded in clay or other materials, provided that the bore in the bowl is shaped in the moulding of the bowl, while the bore or passage in the stem is shaped as above described.

Having thus described my invention what I claim as new and desire to secure by Letters Patent is:—

1. In a tobacco pipe a bowl having a bore therein, said bore contracting towards the bottom of the bowl, the said bore having a recess at one side of the bottom thereof, the

said recess extending downwardly beyond the bottom of the bore whilst the outer wall thereof is substantially parallel with the axis of the pipe bowl, and a pipe stem formed integral with the bowl, said pipe stem having a bore of large diameter therein, the bore in the stem communicating with the said recess above the bottom thereof and adjacent said recess being reduced in area so that a small draught hole of proper size is formed where the bore in the pipe stem emerges in the recess, whereby tobacco pressed into the bore of the bowl is prevented from being pressed against the draught hole and any particle of tobacco which enters the said draught hole can be drawn into the larger bore of the stem so that a constant draught can be exerted on the tobacco which is thus completely consumed in the bore of the bowl.

2. In a tobacco pipe a bowl having a bore therein said bore contracting towards the bottom of the bowl, and a pipe stem formed integral with said bowl, said pipe stem having a bore of large diameter the end of which adjacent the bowl terminates in a conical portion so as to form a small draught hole, the bore of the bowl having an eccentrically arranged circular recess with the outer wall of which the draught hole communicates, said recess being extended downwardly in the bowl below the level of the draught hole and below the bottom of the bore in the bowl, one wall of the recess being substantially parallel with the axis of the pipe bowl, the arrangement being such that when tobacco is pressed into the bore of the bowl the pressure near the draught hole is relieved by the recess which does not become choked with tobacco.

FREDERICK E. V. BEANES.
